BUTT-IN TELEPHONE SYSTEM

Egil Cohrt, Copenhagen, Denmark, assignor to
International Standard Electric Corporation,
New York, N. Y., a corporation of Delaware

Application May 15, 1943, Serial No. 487,196
In Denmark August 22, 1940

7 Claims. (Cl. 179—18)

1

The present invention relates to automatic private branch telephone exchanges in which conversational connections between subscribers take place through cord circuits and no busy tone is given when a subscriber is reached who is already connected to a conversational circuit.

Ordinarily, a caller selecting a busy subscriber is not admitted on this subscriber's connection but receives a busy tone. In P. B. X's for quite special purposes it is necessary, however, that a connection is always established immediately. In such case, it is desirable to send to the subscribers carrying on the original conversation a signal indicating that still another subscriber has joined the connection. It is thus possible for a comparatively great number of subscribers to simultaneously carry on a conversation with one another. P. B. X's thus present problems which do not exist in ordinary systems.

An object of the present invention is to provide a P. B. X circuit in which a subscriber can be released without other subscribers, talking over the same cord circuit, being released.

Another object of the invention is to provide means whereby a subscriber can be released from the connection over which he originally talked and continue the conversation with a new subscriber connected to his line.

In brief I accomplish these and other objects of the present invention as will become more apparent hereinafter, in the following manner:

The cord circuits according to the present invention include a device by means of which a cord circuit at call from a subscriber, who wants to talk to a subscriber who is engaged by a conversational connection through another cord circuit, is connected to this latter connection and moves to listening-in position. In the latter position, a warning tone is flashed to the busy subscribers, and the same is used to lock the original cord circuit as long as at least one of the subscribers who was originally connected to it, is engaged by a conversational connection.

The invention will be more readily understood from the following description thereof and the accompanying drawings which illustrate an embodiment of the invention, by way of example. In the drawings—

Fig. 1 illustrates a subscriber line circuit and a starting circuit;

Fig. 2 illustrates a cord circuit according to the invention; and

Fig. 3 illustrates a circuit for unused lines.

In the subscriber line circuit and starting circuit shown in Fig. 1, each subscriber line is pro-

vided with a combined line- and cut off-relay L_r , whereas a pilot relay S_r and a test resistance are common to a maximum of twenty line circuits.

A starting relay U_{rr} is common to all the subscriber lines of the unit.

When a subscriber desires to make a call and lifts the telephone off the cradle at his station, a line loop is closed, and relay L_r is half attracted and closes its right middle front contact; it is not sufficiently energized for breaking its other contacts.

The pilot relay S_r is energized followed by relay U_{rr} which supplies ground connection to the starting relays in the cord circuits.

15 The calling line is characterized by test potential on the contact e (Fig. 2) of the line finder arc. All idle line finders rotate, and when one of these has found the calling line it stops, and direct ground connection is given from the cord circuit to the c wire, whereby relay L_r is energized strongly, so that it is entirely energized and separates itself from the a and b wires, after which the relays S_r and U_{rr} are released, and the other rotating line finders stop. The test 20 battery is interrupted at the right innermost back contact of relay L_r .

When a line selector at call to a subscriber is adjusted to a subscriber, direct ground is connected to the c wire, so that relay L_r is energized 25 entirely and is interrupted from the a and b wires.

The cord circuit shown in Fig. 2 consists of a 30 50 point line finder SMF , one, or possibly two line selectors SMS_1 and SMS_2 , and a group of relays. The exchange has a capacity of 50 subscribers, when the line selector SMS_1 is applied alone, while a capacity of 99 subscribers is obtained when the extra line selector SMS_2 is applied too.

35 40 Connections to idle subscribers are established in the ordinary way, but no busy tone is given in case of a call to a busy subscriber. In this event, the connection is established immediately after the warning tone has been sent which indicates to the talking subscribers that a third party has just joined the connection.

The cord circuit, over which the original conversation was established, is thereupon locked so long as a conversation is carried on with the 45 50 originally calling or originally called subscriber, or possibly both. The other cord circuits, over which connection is established to a busy line, move to listening-in position, so that microphone feeding current is supplied from the original cord circuit only.

When a calling subscriber lifts the telephone off the cradle, the line relay is energized and gives starting potential to the starting relays L_{sr} of the cord circuit, which relays energize over a jack B_f and battery on the outermost left back contact of relay Ar . The line finder SMF rotates by means of the following circuit: battery, a resistance, the magnet SMFM, the interrupter of this magnet, back contact of relay Dr , a front contact on relay L_{sr} , a back contact on relay P_{br} , a back contact on relay L_{tr} , a normal contact on a selector $SMS2$, normal contact on the selector $SMS1$, the a arc of selector SM in normal position, back contact on relay Ar , back contact on relay Asr and ground.

The line finders SMF in all idle cord circuits rotate and hunt for the calling subscriber who is characterized by test potential on the e contact of the line finder arc, to which the test relay L_{tr} is connected over the outermost left front contact of relay L_{sr} .

When the line finder reaches the contact corresponding to the calling subscriber, the test relay is energized and interrupts the circuit for the line finder magnet, so that the selector SMF stops. Via the front contact of relay L_{tr} and the back contact of relay T_{cr} as well as the innermost right front contact of relay L_{sr} ground connection is established through an 1800 ohms resistance on relay Har to relay Br , which is energized slowly in order to prevent two cord circuits from being connected simultaneously to the same subscriber, relay P_{br} being energized via the outermost right front contact of relay L_{sr} . Relay P_{br} connects ground to the 6 ohms winding of relay L_{tr} , whereby double connection is prevented in known way, because two relays L_{tr} cannot be energized simultaneously when their 6 ohms windings are inserted.

When relay Br closes its front contact, a circuit is closed for relay Dr , which is attracted and through-connects the a and b wires to a feeding relay Asr which is energized, while at the same time ground is connected to the c wire of the subscriber line via the c brush of the line finder, whereby the line relay is entirely energized and switches off the subscriber line and interrupts the starting ground and the test battery. All the other rotating finders stop and from a front contact on relay Dr a circuit is closed for relay Ar which is energized. Relay Ar interrupts the battery from relay L_{sr} , which, however, is already released, so that it can no longer be energized; relay L_{tr} was released together with relay P_{br} when the test battery was interrupted, whereas relay Br is kept energized through a resistance of 2000 ohms on relay Har from the front contacts of relay Asr . Relay C_{br} is energized over the outermost left front contact of relay Har from ground through a pilot relay in the ringing- and tone-circuit; the starting of the tone signal is obtained via the front contact of relay T_{or} .

The following circuit is closed for relay H_{sr} : battery, left outermost front contact on relay Ar , front contact on relay C_{br} , a resistance, winding on relay H_{sr} , back contact on relay F_{tr} , back contact on relay O_{tr} , back contact on relay R_{cr} , right innermost front contact on relay Ar and ground.

Relay C_{br} is then kept energized over the innermost left front contact of relay H_{sr} from ground in the ringing- and tone-circuit in parallel connection with relay T_{or} , which is energized over another front contact on relay H_{sr} . The 2000 ohms resistance on relay Har is short-circuited over the right innermost front contact of relay H_{sr} , so that relay Br is locked direct from the front contact on relay Asr , whereby it is saturated and hence slow in releasing.

5 Dialing tone is sent to the calling subscriber in the following circuit: dialing tone generator, left front contact on relay B_f , $\frac{1}{10}$ MF condenser, the b arc of the selector SM in normal position, left middle front contact on relay Ar , uppermost back contact on relay F_{tr} , a condenser and the a wire of the subscriber line.

The subscriber dials the first digit of the wanted number and relay Asr transmits the impulses via its back contact to the magnet SM in the following circuit: ground, back contact on relay Asr , left innermost front contact on relay H_{sr} winding on relay L_{mr} , back contact on relay T_{cr} , winding on the magnet SMM, a resistance, battery.

15 20 When the selector SM has made the first step the dialing tone is interrupted.

Relay L_{mr} is energized during the impulsing, and closes via its front contact the following circuit for relay Har : battery, winding on relay Har , front contact on relay L_{mr} , back contact on relay T_{cr} , back contact on relay L_{sr} , innermost left front contact on relay Har and to ground.

25 30 Relay Har is energized and locked to ground on relay Dr over its middle left front contact, after which it interrupts its own magnetizing circuit at its innermost back contact.

35 Relay L_{tr} is energized after the release of relays L_{sr} and P_{br} in the following circuit: ground, a winding on relay L_{tr} , back contact on relay P_{br} , front contact on relay H_{sr} , marking line 1, arc c of selector SM in normal position, a resistance, and battery.

40 45 When the first impulse has been received and the selector SM has made one step, relay Har is energized as already mentioned, and the following circuit is closed for the magnet $SMS1M$: battery, a resistance, the magnet $SMS1M$, its interrupter, right innermost back contact on relay S_{dr} , outermost right front contact on relay Har , outermost right back contact on relay T_{cr} , back contact on relay L_{tr} . However, inasmuch as relay L_{tr} is energized, as already mentioned, the selector $SMS1$ rotates only if the first digit consists of two or more impulses.

50 55 As soon as the selector SM releases the marking line No. 1, the circuit for the magnet $SMS1M$ is closed, whereby the selector $SMS1$ rotates. When the first digit is received, relay Asr remains energized, whereas relay L_{mr} is released.

60 65 When the selector $SMS1$ reaches the marking line on which the selector SM is standing, a circuit is closed for relay L_{tr} via the e arc and e brush of the selector $SMS1$, and this relay is energized and stops the selector. The following circuit is closed for relay T_{cr} after the release of relay L_{mr} : ground, right middle front contact on relay Ar , front contact on relay L_{tr} , back contact on relay T_{cr} , back contact on relay I_{mr} , front contact on relay Har , winding on relay T_{cr} and battery.

70 75 Relay T_{cr} is energized and locked via its outermost left front contact to ground on relay Ar and opens at its outermost right front contact the circuit for the selector $SMS1$, so that the finder $SS1$ cannot rotate any more.

If the capacity of the exchange exceeds 50 lines, relay S_{dr} is energized by the tenth digits 6, 7, 8, 9, 0 via the d arc of the selector SM and changes over from the line selector $SMS1$ to $SMS2$.

The subscriber now selects the units digit and relay *Asr* operates in accordance with the dial. The impulses are transmitted direct to the magnet of the line selector via the following circuit: ground, back contact on relay *Asr*, front contact on relay *Hsr*, winding on relay *Imr*, front contact on relay *Tcr*, contact on relay *Sdr*, winding on the magnet *SMSIM*, 48 ohms resistance and battery.

Relay *Lmr* is energized during the impulsive and closes the following circuit for relay *Pbr*: battery, winding on relay *Pbr*, left innermost front contact on relay *Tcr*, front contact on relay *Lmr*, left middle front contact on relay *Har*, front contact on relay *Dr* and to ground.

Relay *Pbr* closes the following circuit for relay *Rcr*: battery, winding on relay *Rcr*, left middle front contact on relay *Pbr*, back contact on relay *Ftr*, back contact on relay *Otr*, back contact on relay *Rcr*, right innermost front contact on relay *Ar* and to ground.

Relay *Rcr* is locked via its own front contact to ground via the back contacts of relays *Otr* and *Ftr* and interrupts its own magnetizing circuit. Relay *Ltr* is released when the selector *SMSI* leaves the marking line.

When the units digit has been received, the selector *SMSI* is adjusted to the line of the wanted subscriber, and relay *Asr* remains energized, whereas relay *Lmr* is released.

When relay *Lmr* is released after the last digit has been received, relay *Pbr* is released (which was locked over the front contact of relay *Lmr*) and the following circuit is closed between the *c* line of the called subscriber and relay *Ftr*: battery, winding on relay *Lr* (line circuit), *c* line, the *c* brush of the line selector, front contact on relay *Hsr*, winding on relay *Ftr*, front contact on relay *Tcr*, left front contact on relay *Cbr*, right innermost back contact on relay *Pbr*, back contact on relay *Ltr*, right middle front contact on relay *A* and to ground.

It should be noted that when relay *Rcr* was energized, the energizing circuit for relay *Hsr* was interrupted, this relay remains, however, energized via the left middle front contact of relay *Pbr* in parallel connection with relay *Tcr* during the impulsive. After the release of relay *Pbr*, the circuit for relay *Hsr* is interrupted, but since this relay releases slowly, it allows relay *Ftr* to energize in case of connection to an idle subscriber via its innermost right front contact. When relay *Ftr* closes its uppermost front contact it is locked in following circuit: battery, winding on relay *Ftr*, front contact on relay *Ftr*, winding on relay *Ftr*, front contact on relay *Tcr*, front contact on relay *Cbr*, back contact on relay *Pbr*, back contact on relay *Ltr*, right middle front contact on relay *Ar* and ground.

Relay *Lr* of the subscriber line is energized in series with relay *Ftr*, and when relay *Hsr* closes its right innermost back contact it remains energized from direct ground connected to the *c* line in following circuit: battery, a winding on relay *Lr* (line circuit), the *c* brush of the line selector, right innermost back contact on relay *Hsr*, lowest front contact on relay *Ftr*, right front contact on relay *Cbr* and to ground.

After the release of relay *Hsr* relay *Cbr* is under control of relay *Rcr* via the lowest front contact of this latter relay.

Ringing signal is sent to the called subscriber via following circuit: ringing generator, front contact on relay *Rcr*, winding on relay *Csr*, right innermost back contact on relay *Otr*, lowest front

contact on relay *Ftr*, *b* line, the subscriber apparatus, *a* line, uppermost front contact on relay *Ftr*, lowest front contact on relay *Rcr*, innermost right front contact on relay *Ar* and ground.

5 The 750 ohms winding of relay *Csr* is shunted by a winding on relay *Rcr*, whereas its other winding is short-circuited by ground on the *a* wire, so that relay *Csr* is made slow in becoming energized.

10 Call back tone is sent to the calling subscriber from the left outermost back contact of relay *Pbr* via a front contact on relay *Rcr* and the *b* wire.

When the called subscriber lifts the telephone off the cradle, the line loop is closed, whereby relay *Csr* receives sufficient current through its right winding for energization, and since relay *Rcr* is locked via a back contact on relay *Csr*, this relay is released immediately and interrupts the ringing and the call back tone and through-connects the conversational connection via two condensers.

25 Relay *Csr* remains attracted via the *a* and *b* wires in series with the called subscriber apparatus and provides microphone feeding current. The conversational circuit is now closed between the calling and the called subscriber.

30 Relay *Cbr*, the magnetization circuit of which is to be interrupted by relay *Rcr*, is then kept energized from the left front contact of relay *Csr*. When relay *Rcr* is released the connection to the ringing- and tone-circuit is interrupted by relay *Rcr*, and this circuit stops.

35 During the conversation the cord circuit is under control of the calling as well as the called subscriber. If the calling subscriber restores the telephone handset to the cradle at his station, thereby normally disconnecting or disengaging the station, the cord circuit is released, and the 40 calling as well as the called subscriber are released immediately. In case the called subscriber restores his telephone first, he releases himself immediately, whereas the cord circuit is not released until the calling subscriber restores his telephone.

45 When the calling subscriber restores his telephone relay *Asr* is released so that relay *Br*, which after the release of relay *Hsr* was locked through a 2000 ohms resistance on relay *Har*, is released and interrupts the ground connection on relay *Dr* which is released and interrupts the subscriber line from the cord circuit. Relay *Dr* interrupts the locking circuit for relay *Ar* which is released and interrupts the locking circuit for relay *Tcr* which also releases. Relay *Ftr* is released together with all the other relays in the circuit.

50 The selector *SM* rotates to normal position by a circuit via its contact arc *a* and its interrupter. 60 When it reaches normal position a circuit is closed for the line selector via its home contact and interrupter, and the line selector moves to normal position, after which the cord circuit is released and ready for new calls.

65 When the called subscriber is released, relay *Csr* is released, the line loop is interrupted, and the circuit for relay *Cbr* is interrupted, so that this relay is released slowly. Ground on the *c* wire, which kept the line relay energized, is interrupted and the line becomes idle. At the same time the locking circuit for relay *Ftr* is opened by the left front contact of relay *Cbr*, and relay *Ftr* is released and disconnects the called subscriber from the cord circuit. The cord circuit

itself is not released until the calling subscriber restores the telephone as explained above.

In case of a call to a busy subscriber, relay *Ftr* cannot attract the armature when the *c* wire is being tested, a direct ground connection being found from the cord circuit, over which the original conversation was established.

Relay *Ftr* then remains in normal position after the units digit has been sent, and relay *Hsr* is released. Relay *Tor* is released slowly after the release of relay *Hsr* and a warning tone is sent during the releasing time of relay *Tor* to the talking subscriber via the following circuit: dialing tone generator *Sg*, left front contact on relay *Br*, condenser right outermost back contact on relay *Hsr*, left front contact on relay *Tor* and the *b* brush of the line selector.

This tone informs the talking subscribers that a third subscriber has joined the connection.

The following circuit is closed for relay *Otr* which is slow in getting energized: battery, winding on relay *Otr*, left innermost front contact on relay *Tcr*, back contact on relay *Tor*, lowest back contact on relay *Ftr*, front contact on relay *Cbr* and to ground.

Relay *Otr* is energized and interrupts the locking circuit for relay *Rcr*, which is released and interrupts the feeding relay *Csr* from the *a* and *b* wires. The calling subscriber is now through-connected to the busy subscriber via the innermost front contacts of relay *Otr*, so that the calling subscribers may now talk to the busy subscriber. Relay *Cbr* is kept energized via a front contact on relay *Otr* and a back contact on relay *Csr*. Via the right outermost front contact of relay *Otr* ground is connected to the *d* brush of the line selector, and via the *d* multiple wire this ground is carried to the cord circuit, over which the original conversation was established, and maintains it, so that it cannot be released which must not happen, since the microphone current is fed from there.

When the calling subscriber is released the cord circuit is released as already mentioned, and relay *Otr* interrupts the ground connection from the *d* multiple wire, so that the busy cord circuit is released in normal way.

During a normal conversation with an idle subscriber, the relays *Kor₁* and *Kor₂* are connected via the relays *Dr* and *Ftr*, respectively, to the *d* brushes of the line finder and the line selector. In case of a call to a busy subscriber the cord circuit, which went to listening-in position, as explained above, connects ground to the *d* multiple wire, so that relay *Kor₁* is energized, in case the call is to a calling subscriber, and relay *Kor₂* is energized, in case the call is to a called subscriber.

At call to a calling subscriber, relay *Kor₁* is energized as explained and connects ground to the relays *Ar* and *Dr*, which are in this way under control of the cord circuit in listening-in position, and the cord circuit is, therefore, locked as long as conversation takes place to the calling subscriber.

At call to a called subscriber, relay *Kor₂* is energized and connects ground to relay *Ar*, which is locked and locks the cord circuit.

At call to a calling subscriber, where the called subscriber is released, the cord circuit is locked via relay *Kor₁*, and when the called subscriber in the original conversation restores his telephone, relay *Csr* is released followed by relay *Cbr*.

Relay *Cbr* interrupts the ground from the *c*

line of the called subscriber, and relay *Ftr* is released, when relay *Cbr* interrupts its left front contact, so that the called subscriber is free.

At call to a called subscriber, where the calling subscriber is released, relay *Asr* is released followed by relay *Br*. Relay *Dr* is released and interrupts the calling subscriber from the cord circuit, whereas the cord circuit (as aforementioned) is locked from the front contact of relay *Kor₂*. When the conversation is finished, relay *Kor₂* is released and interrupts the connection to relay *Ar*, which is released and releases the cord circuit.

On simultaneous calls to the calling as well as the called subscriber, relay *Kor₁* as well as *Kor₂* are energized. If it is desired to interrupt the original conversation and the called as well as the calling subscriber want to continue with the new conversation, they may interrupt the existing connection by depressing the cradle for a moment. When the calling subscriber depresses the cradle relay *Asr* is released followed by relay *Br*, but, since relay *Kor₁* is energized, relay *Dr* cannot be released. Via the back contact of relay *Br* and the front contact of relay *Kor₁* a circuit is closed for relay *Tbr*, which is energized and locks. The relay *Asr* and *Br* are energized a moment later. The original conversation is now interrupted by relay *Tbr*, and feeding current is supplied from the relays *Asr* and *Csr* to the calling as well as the called subscriber.

When the called subscriber depresses the cradle, relay *Csr* is released, followed by relay *Cbr*. Relay *Ftr* is not released, since it is kept energized via the lowest front contact of relay *Kor₂*. At the same time, relay *Kor₂* replaces the ground on the outermost right front contact of relay *Cbr*, so that the line relay is kept energized. The following circuit is closed for relay *Tbr*: battery, winding on relay *Tbr*, lowest front contact on relay *Kor*, left back contact on relay *Cbr*, back contact on relay *Pbr*, back contact on relay *Ltr*, middle right front contact on relay *Ar* and to ground.

Relay *Tbr* interrupts the talking circuit between the calling and the called subscriber. When relay *Csr* energizes again, it is followed by relay *Cbr*.

The cord circuit will not be able to be released until relay *Kor₁* as well as *Kor₂* are released, i. e., when conversations are no longer taking place to the calling or called subscriber.

It should be noted that when the conversation to the calling or called subscriber is interrupted, he will be released from the cord circuit as above explained.

In case a tenth digit is dialed, which is not used for subscriber numbers, a busy tone is given via the *b* arc of the selector *SM* to the calling subscriber.

Fig. 3 shows a circuit for unused lines.

In the usual telephone systems an unused line is characterized by an interrupted *c* line on the *c* arc of the line selector, which causes the cord circuit to send a busy tone. In the P. B. X without test no busy tone is sent, for which reason it is necessary to connect a circuit for unused lines to the line selector arc and interrupt the normal line equipment belonging to unused lines.

When a call is made to an unused line, relay *Cor* is energized and starts the tone. The cord circuit moves to ringing position, but due to the presence of a 500 ohms induction coil, it instantly moves to talking position, after which the busy tone is sent via the front contact of relay *Cor* to

the calling subscriber, who then restores the telephone and releases the cord circuit.

It will be clear that many changes may be made in the construction and arrangement described above without departing from the spirit and scope of the present invention. I therefore do not wish to be understood as limiting myself to the details of construction and arrangement set forth herein.

I claim—

1. An automatic private branch telephone exchange of the type permitting a conversational connection between a first and second subscriber, and in which a third subscriber can be connected to the first or second subscriber without receiving a busy signal, being thus enabled to participate in the conversation, comprising in combination a plurality of cord circuits, a telephone subscriber's station associated with each cord circuit, first means for interconnecting at least a pair of said stations over the respective cord circuits to establish a conversational connection, second means for interconnecting at least one of the remaining cord circuits to said conversational connection for participation in any conversation over said conversational connection, control means operatively connected to said second means for sending a warning signal to the receivers connected to the original conversational connection when one of said remaining cord circuits is connected to said conversational connection, said control means also locking said original conversational connection as long as one of the stations of the original conversational connection remains connected, whereby the subscribers on the original conversational connection are advised by said warning signal when a new subscriber cuts himself in, and conversation with such new subscriber may be continued, due to said locking action, as long as one of the subscribers on the original conversational connection remains in the circuit, though the other cord circuits are interrupted.

2. The system claimed in claim 1, in which said control means includes coupling means actuated by said second means when one of said remaining cord circuits is connected to said conversational connection, whereby said conversational connection is locked as long as conversation takes place over said connected remaining cord circuit.

3. The system claimed in claim 1, in which said control means includes a relay actuated by said second means when one of said remaining cord circuits is connected to said conversational connection, whereby said conversational connection is locked as long as conversation takes place over said connected remaining cord circuit.

4. The system claimed in claim 1, comprising a relay connected to said conversational connec-

tion and actuated by manual disengagement of one of the subscriber's stations thereof, said relay being adapted to release said disengaged station from its cord circuit.

5. The system claimed in claim 1, in which said conversational connection comprises two connected cord circuits, a first and second subscriber's station associated with said two cord circuits, a first relay connected to and actuated by said 10 first receiver, said first relay being adapted to disconnect the cord circuit appertaining to said first subscriber's station, when the latter is manually disconnected; a second relay connected to and actuated by said second subscriber's station, said 15 second relay being adapted to disconnect the cord circuit appertaining to said second subscriber's station when the latter is manually disconnected.
6. The system claimed in claim 1, in which said control means includes a relay actuated by 20 said second means when one of said remaining cord circuits is connected to said conversational connection, whereby said conversational connection is locked as long as conversation takes place over said connected remaining cord circuit and in which said conversational connection comprises two connected cord circuits, a first and a second subscriber's station associated with said two cord circuits, a first relay connected to and actuated by said first station, said first relay being 25 adapted to disconnect the cord circuit appertaining to said first station, when the latter is manually disconnected; a second relay connected to and actuated by said second station, said second relay being adapted to disconnect the cord circuit appertaining to said second subscriber's station when the latter is manually disconnected, all said relays being connected in such a way that upon a simultaneous call to said first and second stations, while the original conversational connection still subsists, the subscriber at said first or second stations may interrupt said original conversation and continue with the new one by momentarily disconnecting the respective station.

45. 7. The system claimed in claim 1, comprising signalling means associated with said cord circuits, said signalling means being adapted to send a busy signal over a cord circuit when a subscriber in said circuit selects a non-existing number.
